UNITED STATES PATENT OFFICE.

DORSEY F. ASBURY, OF WASHINGTON, DISTRICT OF COLUMBIA, ASSIGNOR TO UNITED STATES ORDNANCE COMPANY, OF WASHINGTON, DISTRICT OF COLUMBIA, A CORPORATION OF VIRGINIA.

DETONATING-FUSE.

1,310,046.

Specification of Letters Patent.

Patented July 15, 1919.

Application filed June 24, 1916. Serial No. 105,564.

To all whom it may concern:

Be it known that I, DORSEY F. ASBURY, a citizen of the United States, and resident of the city of Washington, in the District of Columbia, have invented certain new and useful Improvements in Detonating-Fuses, of which the following is a specification.

The objects of my invention are to provide a detonating fuse wherein the fuse proper is mounted for movement in an axial direction relative to the projectile in which it may be mounted to relieve same of excessive stresses upon firing and impact; to so construct the fuse that a relatively great weight of metal will be utilized to initiate the action thereof and thus insure the operation of the fuse upon a very slight retardation resulting from impact against a very thin plate; to provide a fuse wherein the action is automatically controlled by the resistance offered by an object to a projectile with which the fuse is associated, that is to say, when the projectile strikes a thin plate the fuse will be operated quickly but in case the projectile strikes a thick plate the action of the fuse will be delayed; to provide a fuse wherein the danger due to a premature explosion is effectually guarded against; to provide a fuse wherein the detonator runway will not collapse and join the container or pellet in its forward movement; and to provide a detonating fuse which can be safely handled, easily assembled, and which embodies very few parts of exceeding simple construction.

In the drawings chosen to illustrate my invention, the scope whereof is pointed out in the claims,

Figure 1 is a longitudinal section of a fragment of a projectile with my improved fuse in place therein, the fuse being also shown in longitudinal section and the parts in the position they would occupy before the projectile is fired;

Fig. 2, a view similar to Fig. 1 with the parts of the fuse in the position they would occupy after the stock has partaken of its rearward set;

Fig. 3, a view similar to Fig. 1 with the parts of the fuse in the position they would approximately occupy upon impact of the projectile against a target;

Fig. 4, a section on an enlarged scale on the line 4-4 of Fig. 1;

Fig. 5, a section on an enlarged scale on the line 5-5 of Fig. 1, and

Fig. 6, a forward end view on an enlarged scale of the fuse stock.

Referring to the drawings A is a projectile provided with the usual cavity 10 in which is stored the bursting charge 11. The rear end of the projectile is provided with a threaded fuse hole 12. In this instance I have shown the rear end of the projectile formed integral with the body but in large projectiles a portion of the rear end is formed by a base plug and in such instances the latter is provided with the necessary fuse hole.

My fuse proper comprises an adapter B having a cavity 13, said adapter being threaded in the hole 12 and carrying a fuse stock C slidably mounted in the cavity 13. The stock C is provided with an enlarged intermediate portion 14 forming forward and rear shoulders 15 and 16 respectively and the cylindrical face of this enlarged portion bears against the wall of the cavity 13. The rear end of the enlarged portion 14 is stepped to form another shoulder 17 while the rear end of the cavity 13 is reduced to form a shoulder 18 against which the shoulder 17 is adapted to abut to limit rearward set of the stock C. Surrounding the stock C is a corrugated cylindrical buffer 19 one end of which bears against the shoulder 16 while the other end bears against the shoulder 18. Another corrugated cylindrical buffer 20 surrounds the stock C and bears at one end against the shoulder 15 and at its other end against a collar 21 threaded in the forward end of the adapter.

As will be obvious, these buffers hold the stock C in its normal position, the buffer 19 yieldingly holding the stock against rearward set, while the buffer 20 yieldingly holds the stock against forward set. It will of course be understood that the buffer 19 will collapse under the influence of the rearward set of the stock incident to the discharge of the projectile, while the buffer 20 will collapse under the influence of the forward set of the stock incident to the impact of the projectile against a target as clearly shown in Figs. 2 and 3 respectively.

The stock C is provided with an axial fuseway 22 which opens through the rear

end of the stock but does not pierce its forward end. The rear end of the fuseway 22 is closed by a disk 23 having a central opening 24 therein. The stock is also provided 5 with a transverse passage 25 which intersects the fuseway 22 at right angles to the latter. Barriers 26 and 27 are fitted in the passage 25 and are normally held in position to close communication between the forward and rear ends of the fuse way 22 by 10 dowels 28 projecting from plungers 29 movable in a transverse passage 30 drilled through the stock C at right angles to the passage 25. These plungers 29 are backed 15 up by coil springs 30' which normally hold the plungers in locking position but permit same to fly out under the influence of centrifugal force, thus unlocking the barriers and permitting them to also fly out under 20 the influence of centrifugal force to open communication between the forward and rear portions of the fuseway.

Slidably mounted in the fuseway 22 and normally held in the rear end of said fuseway by the barriers 26 and 27 is a detonator container or pellet 31. This container or pellet is of well known construction and carries the detonator 32 in its forward part and an impelling charge 33 in its after end. 30 The detonator 32 is adapted to be exploded by a primer 34 which is fired by impact against a firing point 35 formed on the stock C in the forward end of the fuseway; while the impelling charge 33 is adapted to be 35 exploded by firing a primer 36 carried by the container.

Slots 37 are cut in the stock C to provide a release for the gases in case of premature explosion of the detonator, while the adapter 40 B is provided with an annular groove 38 which surrounds the slots 37 when the parts of the fuse are either in normal position or in the position they would occupy when the stock has partaken of its full rearward set, 45 said groove permitting further expansion of the gases incident to premature explosion of the detonator and also serving other purposes as will presently appear. Pivotally mounted in one of the slots 37 is a firing pin 38' which co-operates with the primer 36 to explode the latter, the container 31 being held against axial rotation, when in its normal position, by a key or feather (not shown) to maintain the firing pin 38 in line 50 with the primer 36. A spring 39 mounted on the stock keeps the firing pin in safe position in a fore and aft direction in the event the stock should accidentally partake of its rearward set without the projectile 55 being fired, while said pin is positively held in safe position under normal conditions by engagement of one end thereof with an abutment 40 on the adapter. A recess 41 is cut in the point of the firing pin 38 to permit

it to shear off as the container drives forward upon explosion of the impelling charge 33. The firing pin 38 is mounted on a pivot 42 which is made relatively small so that the forward set of the stock as the projectile is retarded in flight will shear same. Thus, 70 in case the set of the container is not sufficient to explode the primer 36 the whole weight of the stock C will be brought into action to explode it.

The stock C is provided with a plurality 75 of recesses 42' surrounding the fuseway 22 and stored in these recesses is a booster charge 43, it being noted that the forward ends of the recesses open through the forward end of the stock and are closed respectively by plugs 44.

Danger due to premature explosion of the detonator is guarded against by permitting the gases to expand themselves in driving the stock forward. The shoulder 15 or 85 more particularly the enlarged portion 14 of the stock forms a piston head which, with the corrugated buffer 20 prevents gas leakage between the stock and adapter. Forward movement of the stock is arrested 90 when the shoulder 15 has collapsed the buffer 20 against the collar 21. To prevent the escape of gas into the forward end of the fuseway 22 the barriers 26 and 27 have grooves turned in them forming flanges 45 95 which shear off and cause the barriers to wedge themselves in the fuseway in case of premature explosion of either the impelling or detonating charges.

Assuming the parts to be in the position 100 shown in Fig. 1 it will be obvious that when the projectile is discharged the stock C will set rearwardly and assume the position shown in Fig. 2 and during this movement of the stock the buffer 19 is collapsed. 105 During flight of the projectile the firing pin 38' will move to the position shown in Fig. 2 under the influence of centrifugal force as will likewise the barriers 26 and 27. Upon impact of the projectile both the stock and 110 the container 31 will set forward and as the forward set of the stock will be limited the forward movement of the container will continue until the primer 34 is exploded by 115 contact with the point 35. This explosion of the primer 34 will in turn explode the detonator 32 and the explosion of the detonator will be followed by the explosion of the booster charge 43 and bursting charge 11. It will of course be understood that as 120 the container 31 sets forward the impelling charge 33 will be exploded by the primer 36. In the event the projectile hits a thin plate the stock drives forward into the charge 11 a short distance through the action 125 of inertia due to the weight of the stock, to a greater distance when a thick plate is hit. The container 31 thus has to travel

farther in the latter case than in the former and a greater delay in the action of the fuse is thus effected.

A fuse constructed in accordance with my invention has many advantageous characteristics among which may be mentioned that the booster charge is driven into the bursting charge before detonation. Further, complete safety is insured if the projectile should be dropped as the primer 36 cannot be exploded except by causing the stock to be set back, the firing pin to fly out into its armed position and the stock then to set forward sufficiently to bring the primer 10 against the point of the firing pin. Again a differential pressure is exerted upon the container and stock by the impelling charge so that the velocity of the container in its forward travel will be relatively greater as 15 the travel of the stock in its forward set becomes less, consequently the less the retardation of the projectile the quicker the action of the fuse. By constructing the disk 23 to break away from the stock upon explosion 20 of the impelling charge this variation becomes a maximum.

The stock being mounted for sliding movement in an axial direction all working parts of the fuse are released from the 30 enormous stresses resulting from impact with a thick plate and consequently less subject to deformation. Furthermore, the forward movement of the stock upon impact permits shortening of same and consequently considerable reduction in the length 35 of the fuseway 22 without danger of withdrawing the booster charge too far from the bursting charge of the projectile. During flight of the projectile it will be observed 40 that the firing pin 36 by engaging the wall of the groove 38 acts as a strut to prevent creeping of both the stock and the container.

I claim:

1. In a fuse, an adapter, a fuse stock slidably supported by the adapter, a detonator 45 slidable in the stock, and centrifugally released means carried by the stock and normally holding the detonator against movement.

50 2. In a projectile, a fuse stock slidably supported by the projectile, means yieldable under a predetermined strain normally holding the stock against sliding movement in either direction, and a firing mechanism carried by the stock.

55 3. In a fuse, an adapter, a fuse stock slidably supported by the adapter, means yieldable under a predetermined strain normally holding the stock against sliding movement 60 in either direction, and a firing mechanism carried by the stock.

4. In a projectile, a fuse stock slidably supported by the projectile, a detonator slidable in the stock, and an impelling charge

adapted to be fired by impact of the projectile and exerting a pressure on both the stock and detonator.

5. In a projectile, a fuse stock slidably supported by the projectile, a detonator slidable in the stock, and an impelling charge 70 adapted to be fired by impact of the projectile and exerting a different pressure on the stock and detonator respectively.

6. In a projectile, a fuse stock slidably supported by the projectile, a detonator carried by the stock, an impelling charge, and a firing pin for the impelling charge adapted to hold the stock against sliding movement during flight of the projectile.

7. In a fuse, an adapter, a fuse stock slidably supported by the adapter, a detonator slidable in the stock, and an impelling charge adapted to be fired by impact and exerting a pressure on both the stock and detonator.

8. In a fuse, an adapter, a stock slidably supported by the adapter, a detonator slidable in the stock, and an impelling charge adapted to be fired by impact and exerting a different pressure on the stock and detonator respectively.

9. In a fuse, an adapter, a fuse stock slidably supported by the adapter, a detonator carried by the stock, an impelling charge, and a firing pin for the impelling charge adapted to hold the stock against sliding 95 movement during flight of a projectile.

10. In a projectile, a fuse stock slidably supported by the projectile, a detonator carried by the stock, an impelling charge, a firing pin adapted to be moved to active position under the influence of centrifugal force, and means normally holding said firing pin in inactive position, said holding means being rendered inoperative by the sliding movement of the stock incident to the discharge of the projectile.

11. In a fuse, an adapter, a fuse stock slidably supported by the adapter, a detonator carried by the stock, an impelling charge, a firing pin for the impelling charge normally held in inactive position by engagement with the adapter and released for movement to active position by the sliding movement of the stock incident to the discharge of the fuse in a projectile.

12. In a fuse, a stock having a runway, a detonator mounted for movement in said runway, an automatically opened barrier normally closing the runway in advance of the detonator, and means on the barrier 120 yieldable under the pressure incident to the premature explosion of the detonator to permit a portion of the barrier to be forced into the runway.

13. In a fuse, a stock having a runway, a detonator mounted for movement in said runway, and an automatically opened barrier normally closing the runway in ad-

vance of the detonator, said barrier having a shearing flange adapted to be ruptured by pressure incident to the premature explosion of the detonator whereby the barrier will be forced into the runway by such pressure.

14. In a fuse, an adapter, a fuse stock having an enlarged portion slidably engaged with the adapter, and collapsible members surrounding the stock and engaging respectively at their ends the adapter and the enlarged portion of the stock.

15. In a projectile, a member slidably supported by the projectile, a firing member slidable in the first member, an impelling charge including a primer, and a firing pin on the first member engageable with an abutment fixed relatively to the projectile during flight of the latter whereby the forward set of the member upon impact will drive the primer against the firing pin.

16. In a projectile, a member slidably supported by the projectile, a detonator slidable in the member, an impelling charge includ-

ing a primer, and a firing pin on the member engageable with an abutment fixed relatively to the projectile during flight of the latter whereby the forward set of the member upon impact will drive the primer against the firing pin.

17. In a projectile, a member slidably supported by the projectile, a detonator slidable in the member, an impelling charge including a primer carried by the detonator, and a firing pin pivoted on the member engageable with an abutment fixed relatively to the projectile during flight of the latter whereby the forward set of the member upon impact will first shear the pivot of the firing pin and then drive the primer against said firing pin.

In testimony whereof I hereunto affix my signature, in the presence of two witnesses.
